UNITED STATES PATENT OFFICE.

WILLIAM EDENBORN, OF ST. LOUIS, MISSOURI.

BARB-WIRE MACHINE.

SPECIFICATION forming part of Letters Patent No. 330,686, dated November 17, 1885.

Application filed July 27, 1885. Serial No. 172,801. (No model.)

To all whom it may concern:

Be it known that I, WILLIAM EDENBORN, of the city of St. Louis, in the State of Missouri, have invented a certain new and useful 5 Improvement in Barb - Wire Machines, of which the following is a full, clear, and exact description, reference being had to the accompanying drawings, forming part of this specification, and in which—

10 Figure 1 is a top view of my improved machine. Fig. 2 is a rear elevation. Fig. 3 is a vertical transverse section taken on line 3 3, Fig. 1, looking toward the front of the machine, the knife being omitted. Fig. 4 is a 15 front elevation. Fig. 5 is a side elevation. Fig. 6 is a side elevation, part in vertical section. Figs. 7 and 8 are transverse vertical sections taken on line 7 8, Fig. 1, Fig. 7 showing the dies in their open position, and Fig. 20 8 showing them closed. Fig. 9 is a vertical transverse section taken on line 9 9, Fig. 1, looking toward the rear of the machine. Fig. 10 is an enlarged detail view of the horizontal dies in open position. Fig. 11 is a similar 25 view showing the dies in their closed position. Fig. 12 illustrates a piece of the main wire that has been kinked or bent by the dies. Fig. 13 is an enlarged detail view of the vertical dies in their open position. Fig. 14 is a 30 similar view with the dies closed. Fig. 15 is a view of a piece of a strip showing two kinks made by the vertical dies, and one kink made by the horizontal dies. Fig. 16 is a diagram showing the position of the wires, the guide for 35 the barb-wire, and the stationary knife. Fig. 17 is a similar view, with the addition of the movable knife. Fig. 18 is a similar view to Fig. 17 with the knives forced together to cut the barb-wire. Fig. 19 is a diagram showing the 40 knives or cutters, part of the spindle through which the main wire passes, part of the main wire, and part of the barb-wire before the latter is wound upon the main wire. Fig. 20 is a similar view with the movable cutter ad- 45 vanced to sever the barb-wire wound upon the main wire. Fig. 21 is a transverse section of the main wire, showing the barb as formed in Fig. 20. Fig. 22 shows the barb in side view as formed in Figs. 20 and 21, and shows the 50 ends of the hammer and anvil for completing the barb. Fig. 23 is an end view of the

ribbed anvil shown in Fig. 22. Fig. 24 is a transverse section of the main wire, showing the barb in its completed form. Fig. 25 is a perspective view showing part of the main 55 wire and a completed barb formed thereon.

My invention relates to a barb - wire machine that is automatic in its movements, and in which both the main and barb wires are fed intermittently; and my invention consists 60 in features of novelty herein fully described, and pointed out in the claims.

Referring to the drawings, A represents the bed-plate of the machine, to which is secured the main shaft B by journal-boxes B', and a 65 counter-shaft, B², by journal-boxes B³. The shafts are connected by bevel gear-wheels B⁴. (See Fig. 1.)

The main shaft is provided with a driving-pulley, B⁵, and a small pulley, B⁶, that is connected by belt B⁷ to a pulley, B⁸, on a shaft, B⁹, journaled in boxes B¹⁰, secured to a standard, B¹¹. On this shaft is the ordinary winding-spool, B¹², (see Fig. 2,) the spool being turned through means of the described connection with the main shaft, and reciprocating back and forth in the usual manner as the wire is wound upon it. The belt B⁷ has a 70 tightener consisting of a pulley, U', on a rock-shaft, U, having a crank, U², and a ratchet-wheel, U³, engaged by a pawl, V, pivoted to the frame of the machine. (See Fig. 2.)

Secured to the main shaft at the opposite end from the driving-pulley is a disk or crank, C, provided with a wrist-pin, C', connected by 85 a pitman, C², to a similar pin, C³, projecting from one end of an arm, C⁴, loose on the shaft C⁵, journaled in boxes C⁶, secured to the bed-plate of the machine. Rigidly secured to the shaft C⁴ is a notched disk, C⁷, engaged by a 90 pawl, C⁸, pivoted to the upper end of the arm C⁴, and held against the disk by a spring, C⁹.

As the main shaft revolves it causes the arm to move from the position shown by full lines, Fig. 5, to that shown by dotted lines, 95 same figure, causing the shaft C⁴ to be reciprocated by means of the described connection, and as the arm is being moved back the shaft is held from turning back with it by means of a pawl, C¹⁰, pivoted to the bed-plate of the 100 machine, and having an arm, C¹¹, that extends beneath the main shaft of the machine, where

it is struck by a cam, B¹², on the main shaft, to force the pawl out of contact with the notched disk C¹², rigidly secured to the shaft C⁴. This pawl is moved out of contact with its disk just as the parts are in position to reciprocate the shaft C⁴, and thus does not interfere with the movement of the shaft until a proper time has arrived. The shaft C⁴ effects the intermittent feed of the main wire D, which passes between a roller, D', on this shaft and a similar roller, D², on a short shaft, D³, journaled in boxes D²⁰, that are hollow and fit over the upper ends of posts D⁴, supported by the bed-plate of the machine. Surrounding the posts beneath the boxes are springs D⁵, that act to support or hold the upper roller from bearing with its full weight upon the lower one, and this upper roller, when desired to increase the friction of the rollers upon the main wire, is forced down by means of a cam, D⁶, having a handle, D⁷, pivoted to a pin, D⁸, projecting from a cross-head, D⁹, supported by the posts. (See Fig. 1.) The cam bears upon a leaf-spring, D¹⁰, resting upon projections D¹¹ of the boxes D²⁰. (See Fig. 4.) The shafts C⁴ and D³ are connected by cog-wheels D¹², so that a positive movement is given to the rollers as the shaft C⁴ is turned, as described, and the main wire is thus fed forward intermittently. Before reaching the rollers the main wire passes through an eye, E, of a guide-standard, I, secured to the bed-plate. From the rollers the main wire passes between horizontal dies F and F'. One of the dies has a concave face and the other a convex face, as shown best in Figs. 10 and 11. The die F is stationary, and is held in a standard, F², projecting outward from the bed-plate, by set-screw F³, and the die F' is held by a set-screw, F⁴, in the upper end of a bell-crank lever, F⁵, pivoted at F⁶ to a projection, F⁷, formed upon the bed-plate. (See Figs. 7 and 8.) The lower end of this bell-crank lever is connected by means of a link, F⁸, to a lever, F⁹, pivoted at F¹⁰ to projections F¹¹, secured to the bed-plate. The outer end of this latter lever extends over the counter-shaft B², and is moved vertically by cam B¹³ on this shaft, and as it is raised the die F' is forced toward the stationary die F from the position shown in Fig. 10 to that shown in Fig. 11, causing a crimp, D¹⁴, (see Fig. 12,) to be made in the main wire. From the dies F F' the main wire passes between vertical dies G G', having faces similar to those F F'. (See Figs. 13 and 14.) The die G is stationary, being formed upon and supported by the bed-plate of the machine, and the die G' is movable, being held in the inner end of the lever F⁹, and being moved toward the stationary die by the cam B¹³, which moves the lever, as specified. Thus both the horizontal and the vertical movable dies are operated by the same cam. The two sets of dies are notched, and are one inch and a half (more or less) apart, and form separate kinks D¹⁴ in the main wire, the barbs being formed upon the main wires of these kinks, as

shown in Fig. 25, and are thus held from slipping on the main wire; and, moreover, the kinks allow for expansion in the main wire to prevent its breakage in extremely cold weather. The die G' may be adjusted by a set-screw, G²⁰. From the vertical dies the main wire passes to and through a hollow spindle, H, journaled in boxes H', secured to the bed-plate, and provided with an elongated pinion, H², formed rigidly thereon and engaged by cog-wheel H³ on a shaft, H⁴, journaled in standards H⁵, secured to the bed-plate. The cog-wheel is rigidly secured to the shaft, and has a notched disk, H⁶, engaged by a pawl, H⁷, at one end of an arm, H⁸, supported loosely on a shaft, and connected by its other end to a crank, C¹³, on the counter-shaft B², by means of a pitman or rod, C¹⁴. The pawl is held against the notched disk by spring H⁹, and it will be seen that as the counter-shaft revolves it will, through means of the described connection, cause the shaft H⁴ to be turned intermittently, and likewise causes the intermittent movement of the spindle H through means of its connection with the shaft H⁴. When the shaft is turned, it is held from retrograde movement by a pawl, H¹⁰, pivoted at H¹¹ to the bed-plate and held against the notched disk by spring H¹². (See Fig. 3.) The arm is held against the notched disk by a spring, H¹³, surrounding the shaft H⁴. On the end of the hollow spindle is a finger, H¹⁴, that catches the free end of the barb-wire, (see Fig. 19,) and twists it round the main wire, (see Fig. 20,) and as it twists the barb it is receded by means of a rock-lever, J, pivoted at J' to the bottom of the bed-plate. (See Fig. 6.) Inserted in the upper end of the lever, which is made hollow, is a pin, J², that fits in a circumferential groove in the hub of the elongated pinion H². The pin is held into engagement with the groove by a spiral spring, J³, dropped into the hollow upper end of the lever. The lower horizontal end of this bell-crank lever projects outward and beneath a cam, J⁴, on the main shaft B, (see Fig. 1,) and it will be understood that as this end of the crank is depressed by the cam the pinion, and consequently the hollow spindle to which the pinion is secured, will be moved endwise, and the parts are so adjusted that this movement takes place while the barb is being formed, for the purpose of removing the finger from the barb when the barb is completed, and as the cam leaves the lever the latter is caused to resume its natural position by a spring, J⁵, and as it does so the spindle is moved to its forward position and is ready to form another barb. From the hollow spindle the main wire, carrying the barbs with it which have been cut off, as hereinafter described, passes over an anvil, K, over which is located a hammer, K', on the inner end of a lever, K², pivoted to the upper end of standards K³, supported by the bed-plate of the machine. The outer end of the lever extends over the counter-shaft B² and is operated by cam K⁴ (see Fig. 9) to depress the hammer

and cause the barbs to be pressed from the form shown in Fig. 21 to that shown in Figs. 24 and 25. The parts are so arranged and adjusted that the hammer is operated each time 5 a barb passes between it and the anvil, and the barbs are thus pressed so that their points project at right angles to the main wire, and they are all of uniform shape in this respect. The anvil has two small ribs, K⁶, across its 10 face (see Figs. 22 and 23) to receive the part K⁶ of the barb while the pressing is being done. The outer end of the lever is of sufficient weight to cause the hammer to rise after the cam K⁴ has passed; but to insure the upward movement of this hammer I prefer to 15 also employ a spring, K¹, that connects the outer end of the lever to the bed-plate. From the anvil and hammer the main wire passes to and around a sprocket wheel, L, journaled 20 to the outer end of an arm, L', extending from the bed-plate of the machine, and from this wheel the wire passes to the spool B¹². The barb-wire passes to the machine through an eye, M, in a bracket, M', secured to the bed- 25 plate of the machine. This bracket gives support to a sliding block, M², (see Figs. 1 and 9,) provided with a perforation for the passage of the wire, and also provided with a pawl or dog, M³, forced against the wire by means 30 of the spring M⁴. The block is reciprocated by means of a shaft, M⁵, journaled in a box, M⁶, secured to the bed-plate, to which it is connected by a crank, M⁷, and pin M⁸. The outer end of the shaft is provided with another crank, M⁹, similar to that M⁷, and to this latter crank is connected one end of the pitman M¹⁰, the other end of which is made fast to a crank or disk, M¹¹, on the counter-shaft B². The sliding block thus receives its 40 movement through means of the counter-shaft and the described connection, and as it is moved inward the dog M³ takes hold of or grips the barb-wire and feeds it forward the distance of one barb. As the block is moved 45 in the other direction the dog slips over the wire so as not to carry it backward, and this retrograde movement of the block takes place at the time the barb is being formed upon the main wire, as described. From the sliding block the barb-wire passes through a guide, N, held in a bracket, N', (see Fig. 9,) supported by the bed-plate of the machine. The guide causes the barb-wire to be fed across the main wire, as shown in Fig. 16, in position for its 50 free end to be caught by the finger and twisted around the main wire, as explained.

When the barb has been formed upon the main wire, it is cut off by means of a stationary knife, O, and a movable knife, O'. The 55 knife O is secured to the bracket N' by means of a plate, O², and it may be adjusted endwise when required to compensate for wear by means of a set-screw, O³. (See Fig. 1.) The movable knife O' is secured to a block, O⁴, by means 60 of a plate, O⁵, and it may be adjusted endwise

to compensate for wear by means of a set-screw, O⁶. The block is preferably triangular in shape, and is held between ears N² of the bracket N' by means of pins O⁷. (See Figs. 1 and 9.) The outer end, O⁸, of the block is located over one end of a lever, P, pivoted to the bed-plate, and the other end of which extends beneath a cam, P², on the main shaft of the machine. The block is thus tilted vertically as the main shaft is turned, causing the 70 knife to be moved forward from the position shown in Fig. 19 to that shown in Fig. 20, against the end of the stationary knife, to cut off the barbs, and when the cam leaves the lever the parts resume their natural position, 80 giving room for the barb-wire to be fed again between the knives or cutters.

I claim as my invention—

1. The combination of the standard F², having die F, projection F¹, bell-crank lever F³, 85 pivoted to said projection, and having a die, F', in its upper end, lever F⁹, and a link, F⁸, connecting the levers, substantially as set forth.

2. In a barb-wire machine, in combination with a pair of horizontal and a pair of vertical dies for making kinks in the main wire, a separate mechanism for forming the barbs upon the main wire at the kinks, and a mechanism for cutting the barbs off, substantially as set forth. 90

3. In a barb-wire machine, in combination with horizontal and vertical fixed dies and horizontal and vertical movable dies for forming kinks in the main wire, a separate mechanism for forming the barbs on the main wire 100 at the kinks, and mechanism for cutting the barbs off, substantially as set forth.

4. In a barb-wire machine, the horizontal and vertical fixed dies and horizontal and vertical movable dies secured to pivoted levers 105 connected by a link and operated by a cam, in combination with a separate mechanism for forming the barbs upon the main wire at the kinks, and a mechanism for cutting the barbs off, substantially as set forth. 110

5. In a barb-wire machine, the reciprocating spindle provided with a coiling-finger, in combination with the elongated pinion H², cog-wheel H³ on shaft H⁴, notched disk H⁵, arm H⁶, pawl H⁷, rod C⁴, and counter-shaft B², provided with a crank, C¹, substantially as and for the purpose set forth. 115

6. In a barb-wire machine, in combination with the reciprocating spindle provided with a coiling-finger and a grooved pinion, the rock-lever J, pin J², fitting in the hollow upper end of the lever, a spring, J³, beneath the pin, and cam J⁴ on the main shaft, substantially as and for the purpose set forth. 120

WILLIAM EDENBORN.
